APPARATUS FOR PRINTING, PUNCHING,
AND APPLYING CLOSURE BLANKSGeorge W. Booth, Baltimore, Md., assignor to
Crown Cork & Seal Company, Inc., Baltimore,
Md., a corporation of New York

Application July 24, 1935, Serial No. 32,950

21 Claims. (Cl. 226—84)

The present invention relates to apparatus for printing and punching closure discs and the like from a blank of suitable material, the material being preferably in strip form. As incidental to the printing operation, the apparatus may include drying means so that smearing of the ink in the subsequent operations will be prevented. The apparatus may also include means for coating with wax or the like one or both sides of the material.

The invention, while not limited thereto, is particularly useful in the production of closure discs as disclosed, for example, in my United States Patent No. 1,956,217, granted April 24, 1934. Such discs may have a slight central offset and for the production of this offset, the present apparatus may include suitable forming means.

Desirably, also, the new mechanism may include means for receiving and applying the discs as they are produced.

While the invention relates particularly to apparatus for carrying out a succession of operations such as mentioned above, novelty resides also in sub-combinations and elements of the whole. Further, it should be understood that I use the term "printing" herein in no excluding sense unless expressly qualified, since mechanism for embossing or the like may be substituted for the printing mechanism without change in general principle.

In order that the invention may be thoroughly understood, I have shown in the accompanying drawings, by way of example, a practical embodiment thereof. In the drawings,

Figure 1 is a front elevation of the new apparatus partly in vertical section;

Figure 2 is a plan view of the apparatus of Figure 1;

Figure 3 is a vertical sectional view of the apparatus of Figure 1;

Figure 4 is an elevation of the apparatus as seen from the left of Figure 1;

Figure 5 is an elevation of the apparatus as seen from the right of Figure 1;

Figure 6 shows a detail in elevation;

Figure 7 is a plan view of a strip of material shown as having undergone the printing and punching operations;

Figure 8 is a diagrammatic view in elevation of apparatus comprising printing means, drying means, coating means, forming means, punching means, applying means and feeding means for strip material;

Figure 9 is a plan view of the strip shown in

Figure 8 locating the various apparatus mentioned; and

Figure 10 is a diagrammatic cross section of a disc as produced by the apparatus of Figures 8 and 9.

Referring to the drawings, and first to Figures 1 to 7, reference numeral 10 designates a standard which at its upper end is provided with laterally extending vertical ribs 11 and 12, the standard being provided with a vertical recess 13 between the ribs. The forward faces of ribs 11 and 12 are in the same plane and have secured thereto vertical guide strips 14 and 15 whose adjacent edges are parallel, the strips projecting toward each other beyond the lateral walls of the recess 13. An elongated, substantially rectangular block or slide 16 has lateral grooves 17 and 18 in which are engaged the adjacent portions of the strips 14 and 15 so that the slide is guided for purely vertical movement.

Referring particularly to Figure 3, a rotary shaft 19 is journaled in the upper end of the standard 10 behind slide 16 and in perpendicular relation thereto, this shaft, in the operation of the machine, being continuously driven from any suitable source of power. The reduced end of shaft 19 adjacent slide 16 has secured thereon a crank web 20 which carries a pin 21. Slide 16 carries a pin 22 whose axis is in the same vertical plane as the axis of shaft 19 and pins 21 and 22 are connected by a link or pitman 23. It will be understood that when shaft 19 is rotated slide 16 is vertically reciprocated through the described connections.

A yoke-shaped bracket 24 projects horizontally in front of slide 16 and, as here shown, is integral with a pair of parallel flanges 25 and 26 which are secured against the outer faces of strips 14 and 15 and clear of slide 16 so as not to interfere with the movement of the latter. At their lower extremities, flanges 25 and 26 have integral forwardly extending arms 27 and 28 which, at their extremities merge into a horizontal platen or table 29, this platen being of a width determined by the width of the strip upon which the apparatus is designed to operate. The platen 29 extends a substantial distance to the sides of the standard 10. In front of slide 16, the platen is provided with a recess open toward the latter and generally designated at 30, Figure 3, the side walls of this recess being parallel in the planes of the parallel adjacent edges 27' and 28' of arms 27 and 28, these side walls being denoted by the reference numerals 31 and 32, Figure 1, the outer rectilinear wall of the recess, normal to the

edges 31 and 32, being designated by the reference numeral 33, Figure 3.

The top surface of platen 29 is uniplanar, except that its left hand portion, Figures 1 and 2, is provided with marginal shoulders 34 and 35 spaced apart substantially the width of the strip 36 to serve as lateral guide means for the latter. These shoulders preferably extend up to the edge 31, Figure 1, of the platen recess above described and are of slightly greater height than the thickness of strip 36.

To the right of recess 30 the table is provided with a transversely extending arcuately undercut recess 31, whose transverse extent is slightly more than the width of strip 36. To the right of recess 31, the platen is provided with an end recess 38 which has a width slightly greater than the width of strip 36. The end wall 39 of the recess is downwardly rounded.

At its outer extremity, yoke 24 is provided with a vertical bore whose axis intersects the central longitudinal line of strip 36 as guided by shoulders 34 and 35. In this bore is received the upper threaded end of a stud 40 and retained, with possibility of vertical adjustment, by means of nuts 41 and 42. The stud has a lower threaded end 43 surmounted by an integral abutment shoulder 43', the end 43 being passed through a central aperture in a square plate 44 and threaded into an axial bore of a cylindrical male die 45. Plate 44 is clamped between the die and shoulder 43'. The lower plane face of die 45 lies above the top plane of platen 29 a distance only slightly greater than the thickness of strip 36.

An externally square female die 46 underlies plate 44 and has a central downwardly flared through opening 47 whose upper edge is of a diameter to cooperate with the die 43 and is centered relative to the latter. Die 46 is slidably guided by the walls 31, 32 and 33 of recess 30, the front and rear portions of the top surface of die 46 being slightly shouldered as at 48 and 49 to provide a trackway normally in direct continuation of that provided by shoulders 34 and 35 of the platen.

Studs 50, 51, 52 and 53 are fixed in the corners of die 46 and project upwardly with a sliding fit through apertures in the corners of plate 44, the upper ends of the studs being threaded and provided above plate 44 with lock nuts 54. Interposed between die 46 and plate 44 is a stripper plate 55 which has a central circular opening in which the lower portion of die 45 is slidably received. The stripper plate, which is square, as plate 44, is provided in its corners with openings which receive studs 50 to 53 with a sliding fit, and interposed between plates 44 and 55 are compression springs 56. These springs normally hold the stripper plate against the top of die 46 and the latter with its upper cutting edge below the cooperating edge of die 45 a distance only slightly greater than the thickness of strip 36. The proper adjustment is of course obtainable through adjustment of nuts 54. The trackway constituted by the top surface of die 46 between shoulders 48 and 49 is in substantially flush continuation of the trackway provided by the platen and shoulders 34 and 35 when nuts 54 abut 70 the top of plate 44.

Secured to the lower portion of slide 16 is a carrier 57 which supports a capping head 58 and a magazine 59, the latter being a cylindrical container with its upper open end immediately below opening 47 of die 46. The carrier, capping head

and magazine may be of exactly the same type as disclosed in United States Patent No. 1,956,218, issued April 24, 1934, to George J. Huntley and Harry A. Rau, and are so shown. It will be understood that a packaging tube or other receiver 5 may be used instead of the illustrated capper if the discs are not to be immediately applied.

Slide 16 also has secured to its lower portion flanges 60 and 61 of a yoke 62 which embraces carrier 57 and magazine 59 and directly underlies die 46. For the sake of rigidity, the arms of the yoke are secured also to the carrier 57, as indicated.

A pair of arms 63 and 64 have flanged lower extremities secured on top of the left hand ends 15 of shoulders 34 and 35, Figure 2, and at their upper extremity support a shaft 65 which carries a roll of the strip material 36. Arms 63 and 64 also provide journal portions for the shaft 66 of a roller 67 under which strip 36 is guided to 20 the platen track.

To the right of roller 67, a pair of standards 68 and 69 are secured on top of shoulders 34 and 35, these having vertically slotted upper ends 25 slidably receiving bearings 70 and 71 in which is 25 journaled the shaft 72 of a printing roll 73. Cap plates 74 and 75 bridge the slotted ends of pedestals 68, 69 and have threaded therein adjustable abutment screws 76 and 77 between the lower ends of which and the bearings 70 and 71 are 30 interposed compression springs as at 78, Figure 1. The bearings, shaft 72 and printing rolls 73 are thus yieldingly urged downwardly toward the platen. Pedestals 68 and 69 have arms extending in the longitudinal direction of the platen 35 and carrying upwardly extending links in which are journaled inking rollers 79 and 80, tension springs connecting the links above the rollers so that the latter are yieldingly held against the printing roll.

Inasmuch as it is desired to print on spaced portions of strip 36, the printing roll is provided with a plurality of printing portions or pads 81 spaced about its periphery.

Shaft 72 of the printing roll has fixed thereon 45 a pinion 82 which engages an idler 83 therebelow, the idler being journaled on a stud projecting from pedestal 68. Idler 83 is engaged by a pinion 84 fixed on a shaft 85 whose ends are journaled in a bearing 86 secured beneath the 50 platen and a bearing 87 secured to rib 11. A pinion 88 loose on shaft 85 is adapted to drive the latter, through suitable pawl and ratchet mechanism, in a counterclockwise direction, so that through pinions 82, 83 and 84 55 the printing roll will likewise be driven in a counterclockwise direction, Figure 1.

Positioned in recess 37 is a feed roller 89 fixed on a shaft 90 which is journaled in bearings 91 and 92 secured beneath the platen and in a bearing 93 secured to rib 12. A cooperating feed roller 94, immediately above roller 89 is fixed on a shaft 95 journaled in bearings 96 and 97 fixed to the top of the platen. Shafts 90 and 95 have pinions 98 and 99 fixed thereon respectively, these pinions being of the same size and mutually engaged. Loose on shaft 90 is a pinion 100 which has a radial flange 101 carrying a pivoted pawl 102 and a pawl spring 103. Pawl 102 cooperates with 70 a ratchet 104 fixed on shaft 90. By means of this pawl and ratchet connection, shaft 90 may be driven only in a clockwise direction, Figure 1, shaft 95 being simultaneously driven in a counterclockwise direction through pinions 98 and 99. 75

The rollers 89 and 94, being fixed on their shafts, are driven therewith. The same pawl and ratchet mechanism, reversed as to driving direction, is interposed between pinion 88 and shaft 85.

5 Flanges 60 and 61, Figure 1, have laterally projecting arms 105 and 106 to the extremities of which are secured the upwardly extending racks 107 and 108 whose teeth are adapted to engage pinions 88 and 100, respectively. Shaft 10 65, Figure 1, is removable and insertable through the opening of the spool 109 on which strip 36 is wound to support the same, as shown. The strip is pulled under guide roller 67, printing roll 73 and between dies 45 and 46, the latter die being in its normal lowered position, i.e., below the position shown in Figure 1 so that clearance between the two dies is provided. To provide this clearance, the bottom of stripper plate 15 55 may be slightly relieved as indicated in Figure 20 3. The end of the strip is engaged between feed rollers 89 and 94 and the machine is ready for operation. Since the printing roll will have been operated due to its engagement with the strip as the latter is moved, it will have printed on 25 spaced portions of the strip and the strip will be pulled through just far enough to exactly center one of these portions beneath die 45. Assuming slide 16 to move upwardly upon initiation of rotation of shaft 19, the yoke 62, which lies just 30 below die 46 in the normal lowermost position of the latter, will move the die upwardly to the position shown in Figure 1, so that a circular blank 35 will be struck from the disc. The strip is at rest during this operation.

35 The punched out disc falls into magazine 59 and as the slide and carrier 57 move downwardly, the disc feeding mechanism will be placed in readiness to feed the disc to the capping head, the feeding operation occurring as the carrier 40 57 travels upwardly, all as described in the Huntley and Rau patent before mentioned. No cap will be applied on this first downward movement of the head but on succeeding downward movements caps will be applied to bottles, as at 110, 45 moved into register with the head.

Since upon downward movement of the slide 16, yoke 62 has moved away from die 46, the latter and the stripper plate 55 will be lowered by the springs 56 so that the strip will be cleared 50 from die 45 for free movement therebeneath.

As slide 16 rises, racks 107 and 108, which are in engagement with pinions 88 and 100, will rotate the same and therewith the printing roll and the feed rollers. The gearing ratios are 55 such that the printing roll will be driven at a peripheral speed the same as the speed at which strip 36 is fed by the feed rollers. As upward movement of the slide continues, the teeth of the racks move out of engagement with pinions 88 60 and 100 so that drive of the feed rollers and the printing roll is interrupted before yoke 62 comes into engagement again with die 46. The feeding range of the racks is such that a new printed portion of the strip will be brought into exact 65 register with die 45 and strip 36 will be at rest when yoke 62 again engages die 46 and operatively moves the same.

Thus, all movements of the machine are derived from the reciprocating slide 16. As the 70 slide goes down, a container is capped and as it moves upwardly the strip is fed and printed and a blank is punched. Since the printing roll is urged against strip 36, it could be operatively rotated merely by the strip as the latter is pulled 75 along the platen. Consequently, the positive

drive for the printing roll may conceivably be omitted under some circumstances but to prevent slippage of the strip relative to the roll which might occur due to inertia of the latter, I prefer to provide the positive drive as shown. 5

In Figure 7, two spaced printed portions are indicated at 111 on the strip 36 in advance of the printed portion 112 which is assumed to be at the punching station, reference numeral 113 indicating the shear line. Printed discs have 10 already been punched where the openings 114 appear.

The strip material is of thin ductile metal and preferably has a top facing of paper or the like so as to absorb the ink quickly and prevent 15 smearing. The strip may also have a bottom facing of sealing material such as paper if desired. However, the invention is not limited as to the makeup of the strip and a metal strip may be directly printed upon, particularly where 20 the strip has an eggshell finish and a quick drying ink is used.

In Figures 8 and 9, I have indicated apparatus for carrying out operations in addition to those above described. In these figures, it is assumed 25 that it is desired to produce a cap of the form indicated in Figure 10 and designated by the reference numeral 120. This cap, while substantially flat, has a slight upward central offset forming lower shoulders which are adapted to 30 position the cap accurately on the container to be capped.

Reference numeral 121 designates a roll of strip material which may be assumed to be composed of a metal strip of suitable gauge faced 35 on both sides with paper or the like. As shown in Figure 9, the strip is of a width to enable two series of discs to be struck therefrom. Reference numeral 122 designates a printing roll such as hereinbefore described, except that it is of a 40 width to accommodate two series of printing pads, a cooperating platen being shown at 123. In order to insure drying of the ink, particularly where the strip includes no top paper facing, I provide a drying chamber 124 into which the 45 strip is drawn immediately after the printing operation. This chamber may be heated in any suitable manner, as, for example, by an electric grid as indicated at 125.

Following the drying chamber are a pair of 50 rollers 126 and 127 arranged above and below the strip to contact both surfaces of the latter and supplied from reservoirs 128 and 129 with a fluid coating substance such as wax. Rolls 126 and 127 may have electric heating coils 126' and 55 127' therein. They are preferably geared together in the manner of feed rolls 89 and 94 hereinabove described and may be positively driven exactly as the latter. The printing roll 122 may be conveniently driven from roller 126 60 by means of the chain 130 engaged with sprockets on the drive and driven elements.

Following the coating rollers are two sets of forming dies 131 and 132. Dies 131 have circular bottom recesses 133 of a size to receive 65 dies 132 a short distance. Reference numeral 134 designates movable collars surrounding dies 132 and to which the latter are relatively movable.

In the operation of this forming mechanism, dies 131 and collars 134 are brought together to grip the 70 strip of material, each of these members being preferably moved so that the strip will not be deflected from its prescribed plane of movement. After the strip has been clamped in this manner, dies 132 are moved upwardly to form off- 75

- sets in the strip as shown at 135. The members are then returned to the illustrated relation so that the strip is freed for feeding. These forming devices may be generally as shown in my 5 United States Patent No. 1,956,212, granted April 24, 1934, although with the dies reversed in position, since in the present instance the central portion of the discs must be upwardly offset in order to be printed upon.
- 10 Following the forming dies are two sets of punching dies 136 and 137 which may be of the same general design as those described with reference to Figures 1 to 7, dies 136, however, having cavities for the reception of the offsets 135.
- 15 The vertical position of dies 136 is such as to permit the offsets to move thereunder without interference. At 138 is indicated a receiver which may be associated with a capping head in exactly the same manner as hereinabove described or it may be merely in the form of a 20 cylindrical tube for the packaging of the discs. The feed rolls are indicated at 139 and 140 and may be driven as the rolls 89 and 94 of the first embodiment.
- 25 It will be understood that the feed rollers 139 and 140 are driven intermittently and rollers 126 and 127 may conveniently be of the same size as the feed rollers and similarly driven, their motion being imparted to the printing roll 122 in suitable 30 ratio. The punching apparatus and the forming apparatus are operated while the strip is at rest, the movable die 137 being operated, for example, by means such as yoke 62 of the first embodiment. The relative spacing of the 35 printing, forming and punching devices and the extent of each feeding movement are such that printed portions are brought into exact register with the forming devices and offset portions are brought into exact register with the punching 40 devices upon each feeding movement of the strip.
- In Figure 9, the printed portions of the strip are designated at 141, the formed portions at 135, the shear lines at 142, and the openings from which the discs have been struck at 143.
- 45 When the strip is faced with paper or the like, the drying operation may be unnecessary and, accordingly, the heating unit 125 may be cut off. The arrangement is also preferably such that the coating rolls 126 and 127 and the forming 50 dies 131 and 132 may be rendered inoperative if desired. In printing on metal, the coating rollers, one or both, may be rendered inoperative by removing the coating substance from them and their associated reservoirs. In other words, the 55 arrangement is preferably such that of the drying, coating and forming devices, any one or any two or all may be thrown out of operation. They are placed in or out of operation in accordance with the requirements of any particular job.
- 60 The printing pads may conveniently be of rubber suitably secured to the printing rolls and they may be of a size to print an area of the full dimension of the discs to be punched or the printing may be otherwise distributed or localized 65 with respect to the disc areas. The forming dies, furthermore, may be designed to produce other patterns than that shown. For example, an annular offset, illustrated in my patent first mentioned, may be produced.
- 70 The invention as described is of course susceptible of other variations as to form, arrangement of parts, etc., and, accordingly, it is to be understood that I do not limit myself to the illustrative disclosure herein, but only as in the following 75 claims.

I claim:

1. Apparatus of the class described comprising feeding mechanism for a strip of material, means for printing on spaced portions of the strip, means for punching the printed portions from the strip as closure blanks, means for applying the closure blanks to containers, said last-named means comprising a reciprocable slide, said punching means comprising a movable die separate from the slide, and means carried by said 10 slide for operatively moving said die.

2. Apparatus of the class described comprising feeding mechanism for a strip of material, means for printing on the strip at intervals, means for punching the printed portions from the strip as 15 closure blanks, means for applying the closure blanks to containers, said last-named means comprising a reciprocable head, and means movable with said head for operating said feeding mechanism.

20 3. Apparatus of the class described comprising feeding mechanism for a strip of material, means for printing on the strip at intervals, means for punching the printed portions from the strip as closure blanks, means for applying the closure 25 blanks to containers, said last-named means comprising a reciprocable head, and means movable with said head for operating said printing mechanism.

4. Apparatus of the class described comprising 30 feeding mechanism for a strip of material, means for printing on the strip at intervals, means for punching the printed portions from the strip as closure blanks, means for applying the closure 35 blanks to containers, said last-named means comprising a reciprocable head, said punching means comprising a movable die, and means movable with said head for operatively moving said die and for operating said feeding mechanism.

40 5. Apparatus of the class described comprising feeding mechanism for a strip of material, means for printing on the strip at intervals, means for punching the printed portions from the strip as closure blanks, means for applying the closure 45 blanks to containers, said last-named means comprising a reciprocable head, said punching means comprising a movable die, and means movable with said head for operatively moving said die and for operating said printing mechanism.

50 6. Apparatus of the class described comprising feeding mechanism for a strip of material, means for printing on the strip at intervals, means for punching the printed portions from the strip as closure blanks, means for applying the closure 55 blanks to containers, said last-named means comprising a reciprocable head, said punching means comprising a movable die, and means movable with said head for operatively moving said die and for operating said feeding and printing 60 mechanisms.

7. Apparatus of the class described comprising means for punching closure discs from a piece of suitable material, said means comprising a movable die, a reciprocating head for applying in one direction of movement said discs to containers, and means movable with said head for operatively moving said die during movement of the head in the other direction.

70 8. Apparatus of the class described comprising means for punching closure discs from a strip of material, said means comprising a movable die, a reciprocating head for applying in one direction of movement said discs to containers, means movable with said head for operatively moving said 75

die during movement of the head in the other direction, feeding means for said strip, and means movable with the head for actuating said feeding means during movement of said head in said other direction and prior to the operative movement of said die.

9. Apparatus of the class described comprising a platen, feed rollers for pulling a strip of material along said platen, a printing roll, said strip being engaged between said printing roll and said platen, said printing roll having printing portions spaced around its periphery whereby to print on spaced portions of said strip as the strip is fed, punching means arranged between said feed rollers and printing roll and operative to punch the printed portions from the strip, said punching means comprising a movable die, a reciprocable capping head for applying to containers discs struck from said strip by said punching means, means for imparting operative and return movements to said head, and means for successively actuating said feed rollers to feed the strip and operatively moving said movable die during the return movement of said head.

10. Apparatus of the class described comprising a platen, feed rollers for pulling a strip of material along said platen, a printing roll, said strip being engaged between said printing roll and said platen, said printing roll having printing portions spaced around its periphery whereby to print on spaced portions of said strip as the strip is fed, punching means arranged between said feed rollers and printing roll and operative to punch the printed portions from the strip, said punching means comprising a movable die, a reciprocable capping head for applying to containers discs struck from said strip by said punching means, means for imparting operative and return movements to said head, and means movable with said head during the return movement of the latter for successively driving said feed rollers to feed the strip and operatively moving said movable die.

11. Apparatus of the class described comprising a platen, feed rollers for pulling a strip of material along said platen, a printing roll, said strip being engaged between said printing roll and said platen, said printing roll having printing portions spaced around its periphery whereby to print on spaced portions of said strip as the strip is fed, punching means arranged between said feed rollers and printing roll and operative to punch the printed portions from the strip, said punching means comprising a movable die, a reciprocable capping head for applying to containers discs struck from said strip by said punching means, means for imparting operative and return movements to said head, and means for first actuating said feed rollers to feed the strip and driving the printing roll and then operatively moving said movable die during the return movement of said head.

12. Apparatus of the class described comprising means for feeding a strip intermittently, means for successively punching blanks from said strip, a reciprocating member, and means driven by said member in one direction of movement for operatively actuating the first one of said means to feed the strip and then the other of said means to punch a blank from the strip.

13. Apparatus of the class described comprising intermittently operative feeding mechanism for a strip of material, means for printing on spaced portions of the strip, means for forming the strip to provide offsets centered on the printed portions of the strip, punching means, the feeding steps being of such extent as to bring a previously printed and offset portion of the strip into position to be punched from the strip by said punching means, and means for actuating the punching means while the strip is at rest.

printed portions of the strip, and means for punching the printed and offset portions from the strip.

14. Apparatus of the class described comprising means for punching closures from a suitable piece of material, said means including upper and lower coacting dies of which the latter is hollow, and a capping head beneath said die, the punched closures dropping through said hollow die for direction to said capping head.

15. Apparatus of the class described comprising means for punching closures from a suitable piece of material, said means including a hollow bottom die, a reciprocating capping head beneath said die, the punched closures dropping through said die to be directed to said capping head, and means for operating said punching means during the return movement of said head.

16. Apparatus of the class described comprising means for punching closures from a suitable piece of material, said means including a hollow bottom die, a reciprocating capping head beneath said die, the punched closures dropping through said die to be directed to said capping head, and means moving with said head for operating said punching means during the return movement of said head.

17. Apparatus of the class described comprising means for punching closures from a suitable piece of material, said means including a hollow bottom die, and a capping head beneath said die, the punched closures dropping through said die to be directed to said capping head, said head having closure applying instrumentalities at its lower end and a magazine positioned to directly receive the punched closures from the hollow die and adapted to hold a plurality of the punched closures.

18. Apparatus of the class described comprising means for punching closures from a suitable piece of material, said means including a hollow bottom die, a reciprocating capping head beneath said die, the punched closures dropping through said die to be directed to said capping head, and means for operating said punching means during the return movement of said head, said head having closure applying instrumentalities at its lower end and a magazine positioned to directly receive the punched closures from the hollow die and adapted to hold a plurality of the punched closures.

19. Apparatus of the class described comprising means for punching closures from a suitable piece of material, said means including upper and lower coacting dies of which the latter is hollow, a magazine to which the punched closures pass through said hollow die, and closure applying means to which the closures are passed singly from said magazine as required for application.

20. Apparatus of the class described comprising intermittently operative feeding mechanism for a strip of material, means for printing on spaced portions of the strip, means for forming the strip to provide offsets centered on the printed portions of the strip, punching means, the feeding steps being of such extent as to bring a previously printed and offset portion of the strip into position to be punched from the strip by said punching means, and means for actuating the punching means while the strip is at rest.

21. Apparatus of the class described comprising a platen, feed rollers for feeding a strip of material along said platen, a printing roll, said strip being engaged between said printing roll

and said platen, said printing roll having localized printing portions equally spaced around its periphery whereby to print on spaced portions of said strip as the strip is fed, punching means arranged in the path of the printed strip, means for actuating said feed rollers intermittently to bring the printed portions successively into reg-

ister with the punching means and for concomitantly positively driving said printing roll intermittently, and means for actuating said punching means during the intervals when the strip is at rest to punch the printed portions from 5 said strip.

GEORGE W. BOOTH.
